United States Patent Office

Des. 193,516
Patented Sept. 4, 1962

193,516

CREDENZA

Charles U. Deaton, 9635 W. Colfax Ave.,
Lakewood, Colo.

Filed Dec. 18, 1959, Ser. No. 58,719

Term of patent 14 years

(Cl. D33—7)

FIG. 1

FIG. 2

FIG. 3

FIG. 4

FIG. 5

FIG. 1 is a perspective view of a credenza embodying my new design;

FIG. 2 is a front elevational view thereof;

FIG. 3 is a left side elevational view thereof;

FIG. 4 is a right side elevational view thereof; and

FIG. 5 is a rear elevational view thereof.

I claim:

The ornamental design for a credenza, substantially as shown.
